Filed Sept. 16, 1959, Ser. No. 57,574

Term of patent 14 years

(Cl. D26—14)

FIG. 2.

FIG. 1.

FIG. 4.

FIG. 3.

Fig. 1 is a front elevational view of a one piece shell for an indoor antenna, showing my new design;

Fig. 2 is a side elevational view, the opposite side being substantially a mirror image thereof;

Fig. 3 is a top plan view; and

Fig. 4 is a rear elevational view thereof.

The broken line fragmentary showing of the dipole elements is for illustrative purposes only.

I claim:

The ornamental design for a one piece shell for an indoor antenna, as shown and described.
